UNITED STATES PATENT OFFICE.

JOHANN G. PETERSON, OF JERSEY CITY, NEW JERSEY, ASSIGNOR TO MANHATTAN ELECTRICAL SUPPLY COMPANY, OF JERSEY CITY, NEW JERSEY, A CORPORATION OF NEW JERSEY.

FACE-PLATE FOR ELECTRICAL WALL-RECEPTACLES.

1,236,480.

Specification of Letters Patent. Patented Aug. 14, 1917.

Application filed February 19, 1917. Serial No. 149,384.

To all whom it may concern:

Be it known that I, JOHANN G. PETERSON, a citizen of the United States, residing at Jersey City, in the county of Hudson and 5 State of New Jersey, have invented certain new and useful Improvements in Face-Plates for Electrical Wall-Receptacles, of which the following is a specification.

This invention relates to face-plates for 10 electrical wall receptacles and especially to such face-plates as have openings therein to receive one or more doors. I might note that although such a face plate is primarily intended for association with electrical wall- 15 receptacles and equivalent boxes, it is capable of general use, so that as a matter of fact the title I have adopted is merely a convenient one. These plates are quite thin, and it is the primary purpose of the in- 20 vention to provide means of an effective nature for so connecting a door, or it might be doors with such a plate, as to affect to no appreciable extent the strength of the plate.

In the drawings accompanying and form- 25 ing part of the present specification, I have shown in detail one convenient form of embodiment of the invention which I will set forth fully in the following description, so that those skilled in the art can practice the 30 invention. The latter, however, is not re- stricted in this particular, for I may de- part therefrom in several respects within the spirit of the invention defined by the claim following said description. For in- 35 stance in the showing made the plate is equipped with two doors. While this is ad- vantageous in certain mounts, the invention is not limited in this particular but com- prehends broadly such a plate or equivalent 40 furnished with one or more of such doors.

Referring to said drawings:

Figure 1 is a front elevation of a face-plate involving the invention.

Fig. 2 is a rear view of the same.

Fig. 3 is a longitudinal central section of 45 said face plate.

Figs. 4 and 5 are longitudinal sections on the lines 4—4 and 5—5 respectively of Fig. 2, looking in the direction of the arrows re- 50 spectively and on a larger scale than that of Figs. 1, 2 and 3.

Like characters refer to like parts through- out the several views.

The face or equivalent plate may be of

any suitable construction, that designated 55 by 2 answering satisfactorily in this par- ticular. Said plate as shown is rectangular and is assumed to be of sheet brass and as comparatively thin, being after the usual fashion marginally inset as at 3, although 60 the latter is not always necessary. As shown said plate has an opening 4 which may as represented be practically central of the plate and of any desirable shape, as for in- 65 stance rectangular, although this is a small point. The plate as shown has doors as 5 and 6 which are adapted when closed to fit within the opening and the meeting edges of which have apertures 7 which register to provide a perforation; this, however, is a 70 detail, because the doors might be imper- forate. In Fig. 1 the doors are supposed to be closed, and at this time they are dis- 75 posed wholly within the opening 4. In Fig. 3 they are shown as swung forward or as uncovering the opening 4. As thus far de- 80 scribed the face plate and doors are not un- common, and as I have already noted there may be instances where but a single door is provided, the invention in its broader as- 85 pects not concerning this matter. Asso- 90 ciated with the back of what is shown as the lower door 5 are hinge members such as hooks 8, while the plate 2 is furnished with practically similar hinge members 9 in aline- 95 ment with the members 8 transversely of the plate 2 or of the opening therein. The upper door 6 is likewise furnished on its back with hooks 10, duplicates of the hooks 8 and in transverse alinement with the hooks 11 on the rear of the plate 2. The several co- 100 operating hooks 8 and 9 and 10 and 11 associated rigidly with the doors and plate respectively are intended to receive pivot means such as the pins 12 and 13 respec- 95 tively, the pivot 12 extending through the transversely alined four hooks 8 and 9, while the pivot 13 extends similarly with the upper four transversely disposed hooks 10 and 11. As shown the pivot pins 12 and 13 are con- 105 tinuous from the outer hooks 9 and 10 and 11 and 12, respectively, although this may not in all cases be necessary. As shown the pins 12 and 13 fit against the plate 2 and doors 5 and 6 respectively. I will describe how the respective hooks are connected to the plate and door respectively, and assum- 105 ing the connections to be rigid, it will be

clear that if the pins 12 and 13 have a loose connection with a pair of hooks the doors 5 and 6 can be freely swung open and closed; this, however, is a detail, the elemental consideration being to provide for the proper swing of the two doors.

In the construction shown the hooks 8 are at the ends of a supporting body as the strip or plate 14, while the hooks 10 are at the 10 ends of a practically similar element 16, the strips or plates in question extending transversely of the doors 5 and 6. As they are connected with their doors in similar fashion, a detailed description of the mounting 15 of one plate or strip will apply to the other, and in this connection reference may be had to Figs. 2 and 5 which are assumed to represent the strip 15. Said strip is shown as having counterbores 16 near its ends which 20 bottom in sockets 17 in the upper portions of the door 6 near the sides thereof. From the bottoms of these sockets rise integral studs 18 extending through perforations 19 in the counterbores 16 and headed as at 20 over the 25 bottoms of the counterbores 16. This provides a rigid and substantial way of connecting the plates or butts to the respective doors 5 and 6. At opposite sides of the opening 4 are fastened the strips 21 and 30 with which the hooks 9 and 11 respectively are integral as shown in Figs. 2 and 4. These strips 21 terminate in said hooks 11 and near the hooks are counterbores 22 which fit the sockets 23 in the back of the 35 plate 2 near the corners of the opening 4. From the bottoms of the counterbores 24 extend the studs 25 which project through

perforations 26 in the bottoms of the counterbores 23 and are headed as at 27 over said bottoms as best shown in Fig. 4, thus holding 40 the strips 21 securely in position.

Said strips 21 may as shown be provided between their ends with projections 28 integral therewith, constituting suitable stops and adapted to be engaged by the doors 5 45 and 6 when closed.

What I claim is:

A face plate having an opening, a door when closed disposed in the opening, strips at opposite sides of the door having counterbores, the plate having sockets to receive the counterbores and the bottoms of the sockets being provided with integral rivets, the bottoms of the counterbores having openings to receive the rivets and the rivets being headed 50 over the counterbores, said strips also having open hooks at their ends, a strip having counterbores and extending across the door, the door having sockets to receive the last mentioned counterbores and the bottoms of 55 the sockets having integral rivets extending through perforations in the bottoms of the last mentioned counterbores, and the last mentioned strip having hooks on its inner side, and a pivot extending through the 60 hooks and fitted against the door and plate 65 respectively.

In testimony whereof I affix my signature in the presence of two witnesses.

JOHANN G. PETERSON.
